Ruth D. Silcox, Alexandria, Va.

Application May 19, 1949, Serial No. 2,741

Term of patent 14 years

(Cl. D44—21)

To all whom it may concern:

Be it known that I, Ruth D. Silcox, a citizen of the United States, residing at Alexandria, county of Alexandria, and State of Virginia, have invented a new, original, and ornamental Design for a Combination Mixing and Pouring Pitcher, of which the following is a specification, reference being had to the accompanying drawing, forming part thereof.

Figure 1 is a perspective view of a combination mixing and pouring pitcher, showing my new design;

Figure 2 is a side elevational view; and
Figure 3 is a top plan view thereof.

I claim:

The ornamental design for a combination mixing and pouring pitcher, as shown.

RUTH D. SILCOX.
